UNITED STATES PATENT OFFICE.

ANDREW L. PRENTISS, OF BUFFALO, NEW YORK.

TROLLEY-POLE.

SPECIFICATION forming part of Letters Patent No. 777,304, dated December 13, 1904.

Application filed February 23, 1904. Serial No. 194,736. (No model.)

To all whom it may concern:

Be it known that I, ANDREW L. PRENTISS, a citizen of the United States, residing at Buffalo, in the county of Erie and State of New York, have invented new and useful Improvements in Trolley-Poles, of which the following is a specification.

This invention relates to trolley-poles for railways employing overhead conductors, and particularly to poles of the class which automatically drop to an inoperative position below the conductor and its cross-wires or other supports when the trolley accidentally leaves the conductor, thus preventing injury to the pole and the conductor-supports.

The object of my invention is to provide a pole of this kind which in the event of the trolley running off the conductor is promptly and reliably disconnected from the spring or tension device which holds the trolley against the conductor and which can readily be reengaged with the tension device for restoring the pole to its operative condition.

In the accompanying drawings, consisting of two sheets, Figure 1 is a sectional elevation of a trolley-pole and its base embodying my invention, showing the pole in its normal position. Fig. 2 is a top plan view of the parts. Fig. 3 is a view similar to Fig. 1, showing the pole depressed for restoring the tension of the spring. Fig. 4 is a sectional elevation of the parts, showing their position immediately after the pole has dropped. Fig. 5 is a fragmentary vertical longitudinal section in line 6 6, Fig. 2. Fig. 6 is a horizontal section in line 3 3, Fig. 1.

Similar letters of reference indicate corresponding parts throughout the several views.

A indicates the roof of an electric car, and B the usual swiveling base on which the trolley-pole C is mounted, the pivot on which this base turns being shown by dotted lines at b.

The trolley-pole consists of two parts or sections, the upper one, c, of which carries the trolley c' and is hinged to the lower section by a transverse pivot c'', so as to permit the upper section to swing vertically on the lower section. This lower section is secured to a hub or disk D, which is free to turn on a horizontal shaft d, supported in upright side plates

or standards d', rising from the base B. In the construction shown in the drawings the disk D is provided at its rear edge with a socket d'', in which the pole is clamped.

E is a tension disk or member arranged on one side of the hub-disk D and journaled loosely on the shaft d, the hub-disk being preferably provided with a laterally-extending marginal flange e, which incloses the greater portion of the tension-disk.

F is a tension-spring connecting the tension-disk with the trolley-base and tending constantly to turn said disk in a forward direction. In the preferred construction illustrated in the drawings this spring is secured at its rear end to a rod g, pivoted to the outer side of the tension-disk, and at its opposite end to a rod g', which is pivotally attached to the front ends of a pair of arms or brackets G, extending forwardly from the side plates d'. The front rod g' extends some distance into the tension-spring to form a stop for limiting the forward movement of the rod g when the spring is relaxed, as hereinafter explained, a buffer g'', of rubber or other suitable material, being preferably applied to the rear end of the stop-rod g'.

The hub D of the trolley-pole is normally connected with the tension-disk E by a clutch of any suitable construction, so as to place the pole under the influence of the tension-spring F and cause the trolley to be pressed against the under side of the conductor H like the ordinary pole in common use. I prefer to employ for this purpose a clutch-band I, encircling the periphery of the tension-disk E and secured at one end to the marginal flange of the hub-disk, as shown at i. The opposite end of the band is connected with the short arm of an elbow-lever k, pivoted to said hub-disk, the other arm of this lever being connected by a rod k' with an upwardly-extending arm l, arranged at the inner end of the hinged pole-section c. The pressure of the trolley against the conductor tends to straighten or swing the hinged upper section of the trolley-pole downwardly on its lower section, and this causes the clutch-lever k to be swung in the proper direction to tighten the clutch-band upon the tension-disk E, thus coupling

the hub-disk to the tension-disk and compelling these members to turn forward together under the action of the tension-spring practically as a single member so long as the trolley remains in engagement with the conductor. Should the trolley accidentally run off the conductor, the upper pole-section *c* will swing upward relatively to the lower section, allowing the clutch-band to loosen and uncouple the hub-disk *D* from the tension-disk *E*. As the hub-disk is now free to turn rearwardly on its shaft *d*, the pole drops to a position in which it clears the cross-wires or other supports of the conductor, as shown in Fig. 4 and by dotted lines in Fig. 1, preventing injury to the pole and the conductor-supports.

Any suitable means may be employed for limiting the downward movement of the trolley-pole; but a cushioning-spring *M*, mounted on the base *B* in rear of the disks *D* and *E*, is preferably used for this purpose, as shown in the drawings.

The disconnection of the trolley hub or disk *D* from the tension-disk *E* permits the tension-spring *F* to become relaxed, and in order to again place the same under tension for raising the pole to its operative position a suitable tension-restoring device must be provided. The preferred restoring mechanism shown in the drawings consists of an actuating pawl or lever *n*, mounted on the lower section of the trolley-pole and adapted to engage with a series of ratchet-teeth *n'*, arranged on the periphery of the tension-disk *E*. This pawl is normally retracted out of engagement with said teeth by a spring *n*², but can be projected into the path of the teeth by means of a cord *o*, attached to the upper arm of the pawl and passing rearwardly and downwardly over a guide-pulley *o'*, arranged on the under side of the main pole-section *C*, the cord hanging within convenient reach from the car-platform. Upon pulling this cord the actuating-pawl *n* is first swung into its operative position, and upon then lowering the trolley-pole by a further pull on the cord, as shown in Fig. 3, the pawl is caused to engage with the teeth of the tension-disk *E* and turn the latter rearwardly, thus stretching or tensioning the spring *F*. This depressing movement of the pole causes the cushioning-spring *M* to be compressed, and upon releasing the pole said spring returns the pole to the dotted position shown in Fig. 1. This swinging movement of the pole is repeated until the spring *F* is properly tensioned. The spring *M* thus serves both as a cushion for the pole when the same drops to its inoperative position and as a return device for effecting the upward stroke of the pole when the latter is used to restore the tension of the spring *F*.

P is a pawl or detent for preventing retrograde movement of the disk *E* in tensioning the spring *F*. This detent, which is adapted

to engage with the teeth *n'*, is pivoted to the adjacent bracket *G* of the base *B* and provided with an upwardly-extending arm *p*, having an antifriction-roller *p'*, which is normally located in close proximity to the under side of a retaining-rib *q*, arranged on the outer side of the tension-disk *E*. The detent is held in this position by a spring *r*, attached at one end to the pawl and at its other end to the adjacent side plate of the base *B*, as best shown in Fig. 5. The rib *q* is provided at its front end with a downwardly-curved bill or cam *q'*, which extends below the general plane of the rib, so that when by the release of the trolley-pole the disk *E* is allowed to turn forwardly beyond its normal range of oscillation this cam rides over the roller of the detent, thus depressing the latter and straining the spring *r*. As soon as the point of the cam clears the roller *p* the spring *r* by its reaction raises the detent sufficiently to bring its roller above the point of the cam, as shown in Fig. 4. Upon now turning the disk *E* backward for restoring the tension of the spring *F*, as hereinbefore described, the cam causes the roller to mount the rib *q*, drawing the detent into engagement with the teeth of the disk, as shown in Fig. 3. By this inward movement of the detent the spring *r* is compressed, and as soon as the tail end of the cam-rib *q* clears the roller of the detent the spring throws the detent out of engagement with the teeth of the disk *E*, thus returning the roller to its normal position on the under side of the cam-rib. This rib is so arranged and made of such a length that it holds the detent in positive engagement with the toothed disk *E* until the latter has been turned the requisite distance to properly tension the spring *F*. In order to determine this distance, the disk *E* may be provided on its outer side with a stoppin *s*, adapted to strike the adjacent side plate of the base *B*, as shown.

As the cam-rib *q* positively holds the detent in engagement with the toothed disk *E*, the front portion of the detent, which carries its nose or shoulder, is constructed in the form of a spring or spring-tongue to permit said nose to yield during the intermittent rearward rotation of the disk produced by vibrating the trolley-pole.

It will be understood from the foregoing that in the normal retracted position of the detent the spring *r* is neutral—that is, neither strained nor compressed—and that it is strained while the cam of the retaining-rib *q* rides over the detent-roller and is compressed so long as said roller bears against the upper side of the rib.

T is the usual cord attached to the upper end of the trolley-pole and hanging within reach from the car-platform. This cord is used for lowering the pole by hand in reversing it at either terminus of the railway-line and also for pulling the hinged outer

section of the trolley-pole downwardly relatively to the main section for tightening the clutch-band through the medium of the rod k' and clutch-lever k in recoupling the pole 5 to the tension-disk E and restoring the same to its operative position.

The operation of the pole is as follows: When the trolley is in engagement with the conductor H, the several parts are in the position shown in Fig. 1, the hub D of the pole being clutched to the tension-disk E and the spring F being under tension and tending to hold the trolley-pole against the conductor. When the trolley runs off the conductor, the 10 clutch-band I is loosened, permitting the pole to drop upon the cushion M and allowing the tension-spring F to contract to its unstrained condition. The backward rotation of the disk E, effected by this action of the spring, causes the cam g' of the rib g to ride over the roller of the detent P and then engage under the same, as hereinbefore described and as shown 15 in Fig. 4. To elevate and restore the trolley-pole, the car conductor pulls the cord o for swinging the actuating-pawl n into its operative position and vibrates the trolley-pole by means of this cord for turning the disk E rearwardly and straining the spring F. After 20 turning this disk to the limit of its movement 25 the car conductor seizes the cord T and releases the cord o and allows the pole to swing upward for engaging the trolley with the wire under the action of the spring F, the hub D of the pole having been clutched to the tension-disk E by the tightening of the clutch-band I, as hereinbefore described.

I claim as my invention—

1. The combination of a trolley-pole having sections or members movable relatively to each other, a tension device, a friction-clutch arranged to couple the pole to said tension device, and a tightening device for said clutch operated by the relative movement of said pole-sections, substantially as set forth.

45 2. The combination of a trolley-pole having an upper section or member movable relatively to its lower portion, a tension member, a clutch-band applied to said member and connected at one end to the lower portion of the 50 trolley-pole, and a tightening device connected with the other end of said band and operated by the movement of said upper pole-section relatively to the lower section, substantially as set forth.

55 3. The combination of a trolley-pole having an upper section movable relatively to its lower section, a rotary disk, a spring connected with said disk, a clutch-band applied to said disk and having one end connected therewith, a tightening-lever connected with the opposite end of the band, and an operating connection between said lever and the upper section of the trolley-pole, substantially as set forth.

4. The combination of a trolley-pole having 65 an upper section movable relatively to its lower section and provided with an actuating-arm, a rotary disk, a spring connected with said disk, a clutch-band applied to said disk and having one end connected therewith, a 70 tightening-lever connected with the opposite end of the band, and a connection between said lever and the actuating-arm of the upper pole-section, substantially as set forth.

5. The combination of a rotary disk, a spring 75 connected therewith, a trolley-pole having an upper section movable relatively to its lower section, said lower section being provided with a hub-disk having a laterally-extending flange which surrounds said rotary disk, a 80 clutch-band encircling said disk, and a tightening device for the clutch-band operated by the movement of the upper pole-section relatively to the lower section, substantially as set forth.

85 6. The combination of a trolley-pole having sections or members movable relatively to each other, spring mechanism for holding the pole in its operative position, a clutch for connecting the pole with said spring mechanism, 90 controlling means for said clutch operated by the relative movement of said pole-sections, and a tension-restoring device for said spring mechanism operated by the vibration of the pole, substantially as set forth.

95 7. The combination of a trolley-pole having sections or members movable relatively to each other, a rotary disk or member, a spring connected with said disk, a clutch for connecting the pole with the disk, controlling means 100 for the clutch operated by the relative movement of said pole-sections, and rotating means for said disk operated by vibrating the trolley-pole, substantially as set forth.

105 8. The combination of a trolley-pole having sections movable relatively to each other, a toothed rotary disk, a spring connected with said disk, a clutch connecting the trolley-pole with said disk, controlling means for the clutch operated by the relative movement of said 110 pole-sections, and an actuating-pawl carried by the pole and adapted to engage with said toothed disk, substantially as set forth.

115 9. The combination of a trolley-pole having sections movable relatively to each other, a toothed rotary disk, a spring connected with said disk, a clutch connecting the trolley-pole with said disk, controlling means for the clutch operated by the relative movement of said pole-sections, an actuating-pawl carried by 120 the pole and adapted to engage with said toothed disk, and means for normally holding said pawl out of engagement with the disk, substantially as set forth.

125 10. The combination of a trolley-pole having sections movable relatively to each other, a toothed rotary disk, a spring connected with said disk, a clutch connecting the trolley-pole

with said disk, controlling means for the clutch operated by the relative movement of said pole-sections, an actuating-pawl carried by the pole and adapted to engage with said toothed disk, and an operating-cord connected with said pawl and the trolley-pole, substantially as set forth.

11. The combination of a trolley-pole having sections movable relatively to each other, a toothed rotary disk, a spring connected with said disk, a clutch connecting the trolley-pole with said disk, controlling means for the clutch operated by the relative movement of said pole-sections, an actuating-pawl carried by the lower section of the pole and adapted to engage with said toothed disk, an operating-cord connected with said pawl, and a second cord connected with the upper section of the pole, substantially as set forth.

12. The combination of a trolley-pole having sections or members movable relatively to each other, a rotary disk or member, a spring connected with said disk, a clutch for connecting the pole with the disk, controlling means for the clutch operated by the relative movement of said pole-sections, rotating means for said disk carried by the trolley-pole and operating to turn said disk when the pole is swung downwardly, and a return device independent of said spring for swinging the pole upwardly, substantially as set forth.

13. The combination of a trolley-pole having sections or members movable relatively to each other, a rotary disk or member, a spring connected with said disk, a clutch for connecting the pole with the disk, controlling means for the clutch operated by the relative movement of said pole-sections, rotating means for said disk operated by vibrating the trolley-pole, and a detent device for said disk, substantially as set forth.

14. The combination of a trolley-pole having sections or members movable relatively to each other, a rotary disk or member, a spring connected with said disk, a clutch for connecting the pole with the disk, controlling means for the clutch operated by the relative movement of said pole-sections, rotating means for said disk operated by vibrating the trolley-pole, a detent for said disk, means for normally holding the detent out of engagement with the disk, and means for moving the detent into engagement with the disk when the pole is disconnected from the latter, substantially as set forth.

15. The combination of a trolley-pole having sections or members movable relatively to each other, a rotary disk or member, a spring connected with said disk, a clutch for connecting the pole with the disk, controlling means for the clutch operated by the relative movement of said pole-sections, rotating means for said disk operated by vibrating the trolley-pole, a detent for the disk, a cam carried

by the disk and operating to move the detent into engagement with the disk when the pole is disconnected therefrom, and a spring operating to hold the detent out of engagement with the disk in the normal position of the latter, substantially as set forth.

16. The combination of a trolley-pole having sections or members movable relatively to each other, a toothed rotary disk or member, a spring connected with said disk, a clutch for connecting the pole with the disk, controlling means for the clutch operated by the relative movement of said pole-sections, rotating means for said disk operated by vibrating the trolley-pole, a yielding detent for the disk having an arm, a retaining-rib carried by said disk and adapted to engage with said arm for holding the detent in engagement with the teeth of the disk, said rib having a cam at one end, and a spring connected with said detent and operating to hold said arm in the path of said cam, substantially as set forth.

17. The combination of a trolley-pole having sections or members movable relatively to each other, a toothed rotary disk or member, a spring connected with said disk, a clutch for connecting the pole with the disk, controlling means for the clutch operated by the relative movement of said pole-sections, rotating means for said disk operated by vibrating the trolley-pole, a yielding detent for the disk having an arm carrying a roller, a retaining-rib carried by said disk and adapted to engage under said roller, said rib being provided at one end with a cam-face which extends outwardly beyond the plane of the rib, and a spring connected with said detent and operating to hold said roller adjacent to the outer side of said rib and in the path of said cam, substantially as set forth.

18. The combination of a trolley-pole having sections movable relatively to each other, a toothed rotary disk, a spring connected with said disk, a clutch connecting the trolley-pole with said disk, controlling means for the clutch operated by the relative movement of said pole-sections, an actuating-pawl carried by the pole and adapted to engage with said toothed disk, and a stop arranged to limit the rearward movement of the disk, substantially as set forth.

19. The combination of a base, a trolley-pole having sections movable relatively to each other, a rotary disk having a stop for limiting its rearward movement, a spring connected with said disk, a clutch connecting the trolley-pole with said disk, controlling means for the clutch operated by the relative movement of said pole-sections, and an actuating-pawl carried by the pole and adapted to engage with the toothed disk, substantially as set forth.

20. The combination with a base and a trolley-pole, of a rotary member or disk, a clutch

connecting the trolley-pole with said disk, automatic controlling means for the clutch operating to release the pole from the disk when the trolley leaves the conductor, rods 5 connected with the base and said disk, respectively, and a spiral spring attached at its ends to said rods, one of said rods extending into the spring and forming a stop for limit-

ing the contraction of the spring, substantially as set forth.

Witness my hand this 20th day of February, 1904.
